UNITED STATES PATENT OFFICE.

THOMAS E. WOOD, OF PORTSMOUTH, NEW HAMPSHIRE.

DESIGN FOR COFFIN-PLATES.

Specification forming part of Design No. **7,420**, dated May 5, 1874; application filed February 20, 1874.
[Term of Patent 7 years.]

To all whom it may concern:

Be it known that I, THOMAS E. WOOD, of Portsmouth, in the county of Rockingham and State of New Hampshire, have invented a Design for Coffin-Plates, of which the following is a specification:

The nature of my design is fully represented in the accompanying illustration, to which reference is made.

A is the body of the plate, which is provided with the central oval aperture B, curved apertures F F, and straight apertures E E. On one side of said apertures there is a shield-shaped indentation, C, in the face of the plate, provided with the word "Died," permanently painted or printed thereon. On the opposite side of said apertures there is a like indentation, C', provided with the word "Aged," painted, as aforesaid. These indentations are sunk below the surface of the plate about one-eighth of an inch, the side and top outlines *a b c d* curving inwardly, and the bottom *f* outwardly, as shown. D is an ornamental type-holder, provided with crimped or serrated edges *g g*, inwardly-curving corners *h h h h*, and straight ends *i i*. In outline the main plate has a straight base, E, the ends consisting of corresponding inwardly-sweeping long

curves *k k*. The lower corners are formed with short double inwardly-sweeping curves *l l l l*, and the upper corners with short single inwardly-bent curves *m m*. At the vertex of the plate, or immediately over the central opening B, there is a pyramidal point, *x*, flanked by two corresponding semicircular points, *z z*, and the long and short downwardly or inwardly bending curves *y y p p*. A groove, *j j*, is cut in the face of the plate, near the edge, and corresponding with the conformation of the plate. There is also a like groove, *r r*, around the central opening B, said grooves intersecting over said opening, as shown at *s s*.

Having thus described my design, what I claim is—

The ornamental design for a coffin-plate described, consisting of the oval-portrait aperture B, the indentation C, provided with the word "Died," the indentation C', provided with the word "Aged," and the crimped type-holder D, the conformation of the plate being substantially as specified.

THOMAS E. WOOD.
